Primary Examiner — Samantha Q Lawrence*Assistant Examiner* — Holly M Rodriguez*(74) Attorney, Agent, or Firm* — Nitin Kaushik(57) **CLAIM**

The ornamental design for a microwavable heat pad, as shown and described.

DESCRIPTION

FIG. 1 is a perspective view of a microwavable heat pad design showing my new design.

FIG. 2 is a front view of a microwavable heat pad.

FIG. 3 is a rear view of a microwavable heat pad.

FIG. 4 is a left side view of a microwavable heat pad.

FIG. 5 is a right side view of a microwavable heat pad.

FIG. 6 is a top view of a microwavable heat pad; and,

FIG. 7 is a bottom view of a microwavable heat pad.

Any shading and cross-hatching are not features of the design but are utilized to illustrate the surface contours of the microwavable heat pad design in the drawings.

1 Claim, 7 Drawing Sheets(56)
